UNITED STATES PATENT OFFICE.

HARRY MORRIS, OF CHICAGO, ILLINOIS.

DESIGN FOR AN ADVERTISING DEVICE.

60,054.

Specification for Design.

Patented Dec. 20, 1921.

Application filed April 22, 1921. Serial No. 463,637. Term of patent 7 years.

To all whom it may concern:

Be it known that I, HARRY MORRIS, a citizen of the United States, residing at Chicago, county of Cook, and State of Illinois, have invented a new, original, and ornamental Design for an Advertising Device, of which the following is a specification, reference being had to the accompanying drawing, forming a part hereof, in which— The drawing shows the advertising device in perspective.

I claim:

The ornamental design for an advertising device as shown.

HARRY MORRIS.
